[57] CLAIM

The ornamental design for an automatic document feeder for a printer, as shown and described.

DESCRIPTION

FIG. 1 is a right front side perspective view of an automatic document feeder for a printer showing my new design;

FIG. 2 is a front elevational view thereof;

FIG. 3 is a top plan view thereof;

FIG. 4 is a rear elevational view thereof;

FIG. 5 is a bottom plan view thereof;

FIG. 6 is a left side elevational view thereof;

FIG. 7 is a right side elevational view thereof;

FIG. 8 is a sectional view taken on line VIII—VIII in FIG. 2; and

FIG. 9 is a perspective view thereof showing the feeder in an operative state with a printer attached. The printer and sheet of paper are shown in broken lines for illustrative purposes only in FIG. 9 and form no part of the claimed design.
